JETTY STRUCTURE

George W. Rehfeld, Manhattan, Kans.

Application June 27, 1942, Serial No. 448,813

10 Claims.

(Cl. 61—3)

This invention relates to jetties for controlling banks of streams by retarding erosion and effecting deposit of silt, debris and the like carried in waters flowing therethrough.

It is well known that jetties of this character are subjected to buffeting forces tending to their destruction, particularly in times of high water when the current is swift and carries large quantities of driftwood and the like. Consequently it has been the practice to construct such jetties of structural metal members as these members are of permanent character and when rigidly connected together and laced provide the desired obstruction and withstand the buffeting effects of driftwood while allowing free passage of the water therethrough. However, structural members are relatively expensive and difficult to obtain, particularly within an economical distance from the site of the work.

Therefore, the present invention contemplates the construction of jetties from less expensive and more readily available materials such as concrete, the bulk of which, sand and gravel, is usually obtained at the site of the work, while the cement and reinforcing are available at nearby markets. However, concrete jetties, when made sufficiently strong to withstand the shocks, buffeting and blows from driftage, are too heavy to be self-supporting and sink into the silt so that their effectiveness as an obstruction is relatively short.

It is, therefore, the purpose of the present invention to provide a concrete jetty of sufficiently light construction to be self-supporting upon the river bed and which has the arm members thereof individually formed and flexibly connected to absorb the destructive blows and hammer-like shocks to which they may be subjected.

Another object of the invention is to provide a jetty with a sufficient number of arms to be effective in supporting the lacing and provide stable support on the river bed with sufficient bearing to avoid sinking thereof in quicksands and silt composing a river bottom.

Other objects of the invention are to provide a concrete jetty construction wherein the reinforcement and lacing may consist of stranded cables; and to provide a jetty construction wherein the arm members are individually cast and shaped so that the ends when grouped together form sockets to flexibly locate each individual arm with the axis thereof in intersecting relation with the intersecting axes of the other arms.

In accomplishing these and other objects of the invention, I have provided improved details of

structure, the preferred forms of which are illustrated in the accompanying drawings, wherein:

Fig. 1 is a perspective view of a concrete jetty constructed in accordance with the present invention.

Fig. 2 is a section through the jetty taken through those arms that are located with their axes in a common plane.

Fig. 3 is a detail perspective view of the inner end of one of the arms particularly illustrating the shape thereof whereby the arms when grouped or clustered together in abutting relation provide sufficient flexibility to prevent breaking of the concrete.

Fig. 4 is a fragmentary perspective view of the outer end of one of the arms.

Fig. 5 is a perspective view showing the initial step in the assembly of the jetty.

Fig. 6 is a fragmentary section similar to Fig. 2 showing a modified form of jetty structures.

Fig. 7 is a detail perspective view of the wire connecting member and one of the arms it connects in the form of the jetty illustrated in Fig. 6.

Fig. 8 is a section similar to Fig. 2, taken through a further modified form of jetty.

Fig. 9 is a fragmentary perspective view of adjacent arms of the form of the jetty shown in Fig. 8, the arms being shown in disassembled spaced relation.

Fig. 10 is a perspective view of a further modified form of flexible connection.

Referring more in detail to the drawings:

1 designates a jetty such as used in controlling the bank of a stream and which has a plurality of individually formed arms 2, 3, 4, 5, 6 and 7 arranged with inner ends thereof grouped together and the outer ends extending radially in the shape of a jack. Each arm is individually formed of concrete, preferably consisting of sand, water and cement, which may be mixed together near the job site to form a plastic mass which is cast in a suitable mold, the molds being shaped to provide relatively narrow, elongated arms having side faces 8—9 and 10—11, which may be arranged so that the opposite faces lie in parallel planes or the faces may be tapered from the inner ends 12 toward the outer ends 13 to increase the strength thereof at the center of the jetty and reduce the weight of the outer ends of the arms correspondingly to the bending forces acting along the length thereof. While I have illustrated the arms as being of substantially rectangular cross-section, it is obvious that they may be of other cross-sectional shapes.

The corners between the adjacent side faces are

preferably bevelled, as at 14, from a point spaced from the inner ends thereof to the outer ends to reduce the amount of material therein and yet maintain a high strength to weight ratio. The inner ends 15 of the arms converge from the respective faces, as at 16, and terminate in substantially rounded portions 17, as best shown in Fig. 3. The inner ends of the arms are also provided with transversely arranged openings 18 and 19, staggered with respect to each other and have sufficient taper to drain water therefrom and allow for expansion of ice toward the larger end in case of freezing temperatures, the openings being to pass flexible ties 20 whereby the inner ends of the arms are drawn together to form the cluster, as shown in Fig. 1. The outer ends of the arms have similar transversely staggered openings 21 and 22 which extend parallel with grooves 23 and 24 formed in the outer ends of the arms, as best shown in Fig. 4. The arms thus shaped may be provided with reinforcing, for example ordinary rods or wire, however, I find that lengths of flexible stranded cable 25 disposed longitudinally and substantially coextensive with the axes of the arms are more satisfactory and are preferable. The ends of the cables are unraveled as shown at 26 and spread apart to better reinforce the portions of the concrete surrounding the openings 18-19 and 21-22.

In assembling the arms into a jetty, three of them are placed to form a tripod, as shown in Fig. 5, with the grooved or notched ends upon the ground and with the inner ends brought together with the bevelled faces 15 of one arm resting against the adjacent bevelled faces of an adjacent arm. The other three arms are then supported in a similar but inverted position with the converging faces 16 resting upon the corresponding faces of the previously positioned arms. In this position four of the arms are located with their axes in a common plane and the other two arms extend at substantially right angles thereto. When thus positioned the faces 16 of those arms lying in a common plane form socket-like recesses for the other arms that extend at right angles thereto whereby the arms are retained in centered relation but the rounded surfaces allow for independent pivotal movement of the respective arms under shocks when the jetties are in use as later described.

Prior to lacing, the arms may be temporarily supported in position by suitable spacing rods, or by a jig having shape to retain the desired angular relationship. The inner ends of the arms 2, 3, 4 and 5 are tied or laced together by passing a flexible, preferably stranded, cable 27 through the openings 19 of the respective arms, after which the ends of the cable are drawn together in lapped relation as shown at 28 in Fig. 2 and secured by a clamp 29. A similar cable 30 is then passed through the openings 18 of the arms 2, 7, 4 and 5 and the ends secured by a similar clamp, sufficient tension having been drawn in the respective cables so that the ends of the arms are retained in abutting contact with each other as shown in Figs. 1 and 2.

The outer ends of the arms are then connected by a lacing cable, for example an end of a cable 31 is laid in the groove 23 of one of the arms and then extended in reverse direction through the opening 21, after which the cable is again laid in the groove 23 and extended to the next adjacent arm where the cable is secured in like manner and thence to the next arm, and so on until the place of starting, where the ends are connect-

ed together by a clamp similar to the clamp as previously mentioned. In like manner, a second cable is connected with the ends of the arms lying in a plane transversely to the plane of the previously connected arms so that the cables co-operate with the inner cables in supporting the arms and forming a lacing to supplement the faces of the arms in providing an obstruction and sufficient retardation to flow of water through the jetty and cause sinking of debris, silt and the like which builds up the surface on which the jetty is supported. If desired, intermediate lacing may be provided by equipping the arms with additional openings such as illustrated at 32.

With the arms constructed and assembled as described, the jetties are relatively light in weight and yet effectively withstand shocks to which they are subjected without breaking of the concrete as the respective ends thereof are flexibly supported and one arm is free to move independently of the other arms under the blow of a log or the like carried in the stream.

In placing the jetties they are preferably anchored in rows and the individual jetties are spaced apart by cables passing through crotches formed between opposite arms and secured on the respective sides thereof by fastening devices such as clamps, as in conventional jetty anchorage. The free ends of the cables are anchored to suitable dead men in the bank of the stream so that the entire line of jetties is adapted to position itself and thereby further resist shock that might tend to shatter the arms. The jetties when thus anchored have three of the arms supported upon the bed of the stream and the outer ends thereof become imbedded, while the other arms extend outwardly and upwardly to provide the necessary obstruction in effecting a deposit of debris, silt and the like carried in the water flowing through the jetties.

Attention is directed to the fact that should the arm of a jetty break, the flexible cables forming the reinforcing provide a flexible anchorage to retain the broken sections together and allow for movement thereof without fracturing the reinforcement.

The jetty shown in Figs. 6 and 7 is substantially the same as that just described, with the exception of the flexible connection for the inner ends of the arms. In this arrangement the inner ends of the arms are provided with axial bores 33 to receive the ends 34 of crossed rods 35 that are secured together at their crossing points by welding or the like, as shown in Fig. 7. In this construction the arms are assembled by sliding the inner ends thereof onto the respective terminals 34 of the rods as shown in Fig. 6. When the lacing is applied, as described in the preferred form, the arms are retained upon the terminals of the connecting member but the connecting member provides sufficient movement of the arms under force of a blow to absorb the shock which would ordinarily be destructive to the concrete.

In the form of the invention shown in Figs. 8 and 9, the abutting arms 36-37 and 38-39 are related in pairs, that is the flexible reinforcing 40 extends through and forms the reinforcing of an aligning arm. The reinforcing cable 41 of the arm 42, however, extends through a channel-like bore 43 of the aligning arm 44, the bore starting within the axis of the arm 44 and emerging at a spaced point on the side thereof so that after the connecting portion of the cable for the arms 36 and 37 is crossed with that of the arms

38 and 39, the ends of the arms 41 and 43 may be brought together and seated in the sockets formed by the interconnected arms, the free end of the cable 41 being extended through the channel-like opening. The portion of the cable extending from the channel-like opening is then wrapped about the arm and secured in a suitable manner to retain the assembly. In this form the arms are shown in sections 46 and 47, which are flexibly interconnected by the reinforcing to further enhance flexibility of the jetty.

Fig. 10 shows a connection similar to that illustrated in Fig. 7, however, the pintles 45 are formed of separate pieces 48, 49 and 50, two of which, 48 and 49, are bent at right angles and arranged oppositely to each other so as to pass the third member 50 therebetween. The members, being linked together, provide for greater flexibility than the welded form shown in Fig. 7.

From the foregoing it is obvious that I have provided a light weight jetty construction which is well adapted to be formed of concrete and which is capable of withstanding the shocks to which such jetties are subjected.

What I claim and desire to secure by Letters Patent is:

1. A concrete jetty including, members arranged in converging relation with ends thereof in abutting contact to form a substantially tripod support, arm members having ends movably engaged with the abutting ends of said support and diverging outwardly, means retaining said ends in movable contact, and lacing connecting said members.

2. A concrete jetty including, a plurality of radially extending arm-like members having bores in ends thereof, interconnected rod members having terminals extending into said bores to retain said arm-like members in assembly, and lacing connecting outer portions of said arm-like members.

3. A concrete jetty including, pairs of aligning arms, flexible reinforcing members in said arms and connecting the arms of said pairs, the connected ends of the arms of the respective pairs being spaced apart to provide movement therebetween, said pairs being arranged in crossing relation with the connected ends of the arms in contact whereby one arm is adapted to have slight rocking movement relative to the other arms, and lacing connecting said arms to maintain said arms in assembly.

4. A concrete jetty including, pairs of aligning arms, flexible reinforcing members in said arms and connecting the arms of said pairs, the connected ends of the arms of the respective pairs being spaced apart to provide movement therebetween, said pairs being arranged with the connected ends of the arms in contact whereby one arm is adapted to have slight rocking movement relative to the other arms, and lacing connecting said arms to maintain said arms in assembly, at least one of said reinforcing members being loosely threaded through an opening in one of the arms and adapted to be attached to said arm after assembly of the arms in said crossed relation.

5. A concrete jetty including, a plurality of radially extending arm-like members having bores in ends thereof, rod members interlinked with each other, a rod member extending through the linked members, said rod members having terminals extending into said bores to retain said arm-like members in assembly, and lacing connecting outer portions of said arm-like members.

6. A concrete jetty including, lower members arranged in converging relation with ends thereof in abutting contact to form a substantially tripod support, upper arm members having ends engaged in abutting contact with the ends of the lower members of said support and diverging upwardly and outwardly, and cables connecting the abutting ends of said members to retain the shape of the jetty.

7. A jetty including a plurality of individually formed radially arranged arms extending outwardly from a common central point and upwardly and downwardly therefrom and having their inner ends in actual abutting relationship, means for flexibly connecting the inner abutting ends of the arms and maintaining the same in substantially abutting relationship and providing individual pivotal movement of the arms, and means for connecting the outer ends of the arms with one another and cooperating with said flexible means to secure the arms in an upright self sustaining structure.

8. A jetty including a plurality of individually formed radially arranged arms extending outwardly from a common central point and upwardly and downwardly therefrom and having their inner ends in actual abutting relationship, said arms having openings in their inner abutting ends, flexible means extending through said openings and connecting the inner abutting ends of the arms together and providing for individual pivotal movement of the arms, and means for connecting the outer ends of the arms with each other and cooperating with said flexible means to secure said arms in an upright self sustaining structure.

9. A jetty including a plurality of individually formed radially arranged arms extending upwardly and downwardly from a common central point and having their inner ends in actual abutting relationship, and flexible means having at least two spaced apart connections with the respective arms for connecting the arms together forming an upright self sustaining tetrahedron.

10. A jetty including a plurality of individually formed radially arranged arms extending upwardly and downwardly from a common central point and having their inner ends arranged in actual abutting relationship, the downwardly extending arms providing a substantially tripod support, and flexible means having at least two spaced apart connections with the respective arms for flexibly connecting the arms together forming an upright self sustaining structure and providing for limited independent movement of said arms under shock.

GEORGE W. REHFELD.
